UNITED STATES PATENT OFFICE.

LEWIS B. BRIDGES, OF BROOKLYN, NEW YORK, ASSIGNOR TO RAMP BUILDINGS CORPORATION, OF NEW YORK, N. Y., A CORPORATION OF DELAWARE.

BUILDING.

Application filed January 31, 1921. Serial No. 441,332.

To all whom it may concern:

Be it known that I, LEWIS B. BRIDGES, a citizen of the United States, and resident of the borough of Brooklyn, in the county 5 of Kings, city and State of New York, have invented certain new and useful Improvements in Buildings, of which the following is a specification.

This invention relates to improvements 10 in buildings of the type in which groups of relatively staggered floors are connected by ramps.

One object of the present invention is to provide an arrangement of the groups of 15 floors and the ramps in buildings of this type affording maximum economy of floor space.

A further object of the invention is to provide a building especially adapted for 20 use as a garage and in which the ramps and groups of floors are so arranged as to greatly facilitate the driving of vehicles to storage spaces on the several floors, thus avoiding congestion and delay during those periods 25 when incoming or outgoing traffic is heavy.

In the drawings:

Fig. 1 is a horizontal sectional view taken on the line I—I of Fig. 3, showing one 30 form of building embodying the invention, parts of certain of the floors being broken away;

Fig. 2 a vertical sectional view on the line II—II of Fig. 1;

Fig. 3 a vertical sectional view on the line III—III of Fig. 1;

Fig. 4 a horizontal sectional view on the line IV—IV of Fig. 5, showing another form of building embodying the invention;

Fig. 5 a vertical sectional view on the line V—V of Fig. 4; and

Fig. 6 a vertical sectional view on the line VI—VI of Fig. 4.

In both forms of building illustrated the 45 ground area within the four outer walls 1 of the building is divided into two parts, one of which is rectangular and entirely surrounded by the other part. The two parts of the ground area are separated by 55 two parallel dividing walls 2 and 3 connected at their ends by two parallel dividing walls 4 and 5.

A group of superposed floors 6 overlies that part of the ground area between the 55 outer walls and the dividing walls, and a

second group of superposed floors 7 overlies that part of the ground area located within the four dividing walls. The floors 7 are located in planes intermediate the planes of the floors 6 and a plurality of ramps connect the floors 6 and 7 in such a manner that vehicles or persons may travel from the ground level to the uppermost floor of the building along a substantially helical path. The building has two roof sections 65 at different levels, the roof section 8 overlying the group of floors 6 and the roof section 9 overlying the group of floors 7.

A suitable doorway 10 in one of the outer walls of the building gives access to the lowermost one of the group of floors 6, preferably at a point opposite the entrance to the ramp leading from said floor to the lowermost one of the group of floors 7. The outer walls 1 are provided with suitable windows 75 11, and the dividing walls may be also provided with windows if desired.

In the building shown in Figs. 1 to 3, the ramps extend through the dividing walls 4 and 5. A pair of similarly inclined ramps 30 12 extend from the lowermost one of the group of floors 7, through the oppositely disposed walls 4 and 5 to points on the first and second floors 6 at opposite sides of the group of floors 7. The second one 35 of the floors 7 is connected by two similarly inclined ramps 13 which extend through walls 4 and 5 and connect the second floor 7 with the second and third floors 6. The two ramps 13 are inclined oppositely to the two ramps 12 and are located in a vertical plane at one side of and parallel with a vertical plane intersecting the two aligned ramps 12. It will be obvious that the pairs of ramps 12 and 13 may be duplicated as often 95 as required to connect all of the floors of a building of any height. As the building shown in Figs. 1 to 3 has only three floors in each group, the third floor of the group of floors 7 has only one ramp 12 connected therewith, this ramp extending through wall 4 to the third one of the group of floors 6 and being located in the same vertical plane as the lower pair of ramps 12. The dividing walls 4 and 5 are provided with openings 14 100 at the points where the ramps extend through said walls, said openings extending the full width of the ramps and being made sufficiently high for vehicles to pass through the openings. A portion of the floor and 110

dividing wall above each ramp, at the junction of the floor and dividing wall, may be cut away to increase the height of the openings 14, if desired. Guard walls 15, or any other suitable safety means, may be provided along the longitudinal side edges of the ramps 12 and 13. When employed as a garage, the space on the floors may be divided into individual storage spaces or compartments for motor vehicles by partitions or curbing 16, suitable corridors or driveways being provided connecting all the ramps and also affording access from the ramps communicating with each floor to the storage spaces on said floor, as shown more clearly in Fig. 1.

In the construction shown in Figs. 4 to 6, the ramps 12 and 13 do not extend through the dividing walls 4 and 5 but are located wholly at one side of said walls. In this construction the ramps 12 and 13 are located adjacent the dividing walls 2 and 3, respectively, or at opposite ends of the central group of floors 7. This arrangement increases the head-room at openings 14, and it will also be observed that one edge of one ramp of each pair is protected by the adjacent dividing wall, thereby affording a saving in the construction of guard walls for the edges of the ramps.

It will be observed that each pair of aligned ramps connects three floors in such a way that a vehicle may drive in a direct line from the lowermost to the highest one of the three floors. This greatly facilitates the ease and rapidity of ascent and descent. By providing alternate pairs of ramps of reverse inclination, the distance of travel from bottom to top of the building is reduced to a minimum.

What I claim is:

1. A storage building having two groups of vertically spaced storage levels arranged one within the other and connected by a continuous spiral passage for wheeled vehicles extending around the inner group of storage levels, the levels of one group being located in planes intermediate the planes of the levels of the other group.

50 2. A building having two groups of floors, the floors of one group being located in planes intermediate the planes of the floors of the other group, and a series of ramps cooperating with portions of the floors in the order of their height to form a continuous passageway crossing different edges of successive floors of one group.

60 3. A building having groups of floors overlying different parts of the ground area of the building, and a series of ramps cooperating with portions of the floors to form a passageway connecting all of the floors in the order of their height and crossing alternate floors of one group at different points, 65 the floors in said last-mentioned group be-

ing located in planes intermediate the planes of the floors connected therewith by said ramps.

4. A building having two groups of superposed floors overlying different portions of the ground area of the building, the floors in one group being located within the planes of the outer edges of the floors of the other group, and a series of ramps connecting all of the floors and cooperating with portions of the floors to form a continuous passageway, said ramps being arranged in pairs in two different vertical planes with the successive pairs of ramps inclined in opposite directions.

5. A building comprising outer walls, two groups of floors overlying different portions of the ground area of the building and arranged with the floors of one group staggered vertically relatively to the floors of the other group, and ramps connecting all of the floors of the two groups in the order of their height, each floor of one group being connected with the next higher and lower floors of the other group by two similarly inclined ramps.

6. A building comprising outer walls, two groups of floors arranged one within the other with the floors of one group in planes intermediate the planes of the floors of the other group, and a series of ramps cooperating with opposite end portions of successive floors of the inner group and portions of successive floors of the outer group to form a continuous passageway connecting all of the floors.

7. A storage building having two groups of storage levels arranged one within the other with the levels of one group located intermediate the planes of the levels of the other group, and ramps connecting the two groups of levels, said ramps being arranged so that one end of each level of the inner group is connected with the next higher and lower levels of the other group by two ramps inclined in the same direction.

8. A building having two groups of superposed floors overlying different parts of the ground area of the building and arranged with the floors of one group in planes intermediate the planes of the floors of the other group, one of said groups of floors having portions thereof located at different sides of the other group of floors, and ramps connecting all of the floors of the two groups in the order of their height, each floor of one group being connected with portions of the next higher and lower floors of the other group located at opposite sides thereof by two ramps inclined in the same direction.

9. A building having two groups of superposed floors overlying different parts of the ground area of the building, the floors of one group being located in planes intermediate the planes of the floors of the other

group and one of said groups of floors having parts thereof located at opposite sides of the other group of floors, and a series of ramps connecting all of the floors, said 5 ramps being arranged in pairs with the two ramps of each pair connecting one floor of one group with the next higher and lower floors of the other group at opposite sides of the floor with which both ramps are connected, the pairs of ramps being inclined alternately in opposite directions.

10. A building having two groups of vertically staggered floors connected by ramps, said ramps being arranged in pairs, each 15 pair of ramps connecting one floor of one group with the next higher and lower floors

of the other group at points at opposite sides of said floor, the two ramps forming each pair being inclined in the same direction.

11. A building having two groups of vertically staggered floors, and ramps connecting all of said floors, each floor of one group being connected at oppositely disposed points by one pair of said ramps with the next higher and lower floors of the other 25 group, the pairs of ramps being inclined alternately in opposite directions and the oppositely inclined pairs of ramps being arranged in two parallel vertical planes.

In testimony whereof I hereunto affix my 30 signature.

LEWIS B. BRIDGES
